(57) **CLAIM**

The ornamental design for a beverage generating machine front face, as shown and described.

DESCRIPTION

FIG. 1 is a perspective view of an embodiment of a beverage generating machine front face showing our design; FIG. 2 is a front elevational view of the embodiment of the beverage generating machine front face of FIG. 1.

FIG. 3 is a left side elevational view of the embodiment of the beverage generating machine front face of FIG. 1. FIG. 4 is a right side elevational view of the embodiment of the beverage generating machine front face of FIG. 1.

FIG. 5 is a rear elevational view of the embodiment of the beverage generating machine front face of FIG. 1. FIG. 6 is a top plan view of the embodiment of the beverage generating machine front face of FIG. 1.

FIG. 7 is a bottom plan view of the embodiment of the beverage generating machine front face of FIG. 1. FIG. 8 is a perspective view of another embodiment of the beverage generating machine front face;

FIG. 9 is a front elevational view of the embodiment of the beverage generating machine front face of FIG. 8. FIG. 10 is a left side elevational view of the embodiment of the beverage generating machine front face of FIG. 8.

FIG. 11 is a right side elevational view of the embodiment of the beverage generating machine front face of FIG. 8. FIG. 12 is a rear elevational view of the embodiment of the beverage generating machine front face of FIG. 8.

FIG. 13 is a top plan view of the embodiment of the beverage generating machine front face of FIG. 8. FIG. 14 is a bottom plan view of the embodiment of the beverage generating machine front face of FIG. 8.

FIG. 15 is a perspective view of yet another embodiment of the beverage generating machine front face;

FIG. 16 is a front elevational view of the embodiment of the beverage generating machine front face of FIG. 15.

FIG. 17 is a left side elevational view of the embodiment of the beverage generating machine front face of FIG. 15.

FIG. 18 is a right side elevational view of the embodiment of the beverage generating machine front face of FIG. 15.

(Continued)

FIG. 19 is a rear elevational view of the embodiment of the beverage generating machine front face of FIG. 15.

FIG. 20 is a top plan view of the embodiment of the beverage generating machine front face of FIG. 15; and, FIG. 21 is a bottom plan view of the embodiment of the beverage generating machine front face of FIG. 15.

In the drawings, the broken lines illustrate environmental subject matter only and do not form any part of the claimed design.
